UNITED STATES PATENT OFFICE.

JOHN T. CORBETT, OF AURORA, ILLINOIS.

FIRE-BOX FOR BOILERS.

SPECIFICATION forming part of Letters Patent No. 340,102, dated April 20, 1886.

Application filed March 2, 1886. Serial No. 193,737. (No model.)

To all whom it may concern:

Be it known that I, JOHN T. CORBETT, of Aurora, in the county of Kane and State of Illinois, have invented certain new and useful 5 Improvements in Fire-Boxes for Boilers and in Parts Connected Therewith; and I do hereby declare that the following is a full, clear, and exact description of the invention, which will enable others skilled in the art to which it applies to make and use the same, reference being had to the accompanying drawings, and to letters of reference marked thereon, which form a part of this specification.

My improvements relate to the fire-box and 15 its connection with the boiler, and will clearly appear from the following description.

I have shown my invention as applied to a magazine-boiler, and in which the magazine extends in a curve from the fire box or pot 20 upward around the exterior of the boiler, as in my application for United States Letters Patent, Serial No. 185,284, filed December 10, 1885.

In the drawings, Figure 1 is a cross-section 25 through the fire-box, magazine, and horizontal boiler; and Fig. 2 a vertical longitudinal section, showing also the connection of the fire-box with the boiler.

The fire-box A is hollow, having within it 30 an ample water-space, b. It is preferably made of cast-iron, but may, if desired, be made of boiler-plate and riveted, and it is, as shown, closed at all sides, top, and bottom, the water-space b having direct connection with the water in the boiler by means of the pipes C C, one on each side of the boiler.

The fire-box is preferably made circular, but it may be square or of any other suitable 40 shape, or conformable to or adapted for the shape of the furnace.

The fire-box I prefer to make with a projection or flanged portion, d d, which may also be hollow, as shown, to increase the inclosed water-space, and this permits it to be readily 45 set in the brick-work or masonry of boilers of various constructions, the fire-box being an independent piece of the structure, and not integral with or forming a part of the walls of the furnace or boiler, and the grate bar or bars

or the support for the same may, by reason of 50 the form of the fire-box, be attached to and held by it, as shown at e e in Fig. 1.

In the construction shown the inner edge of the top of the fire-box, as seen at f f, forms a rest for the end of the curved part of the 55 magazines G G. In some cases only one magazine G may be made, extending up at one side only of the boiler.

The large water-holding space b, in conjunction with the large heating-surface of this 60 fire-pot in direct proximity to the burning fuel, largely increase the steam-generating capacity of the boiler, and these, through the agency of the pipes C C, afford means whereby a constant and perfect circulation of water 65 is at all times secured. It will also be readily understood that besides these advantages the water within this fire-box (which may be considered as an endless tube) affords a protection against the destructive tendency of the 70 fire, and renders the fire-box as durable as the boiler itself. The magazines when employed also further increase the steaming capacity of the boiler.

Other forms of fuel-supplying magazine or 75 magazines may be used, so long as it or they communicate directly with the fire-box, and the latter, as shown, is located under the boiler, and the pipes C, as also the magazine or magazines G, are inclosed within the ma- 80 sonry or outer walls, substantially as shown. The heat generated is therefore almost entirely utilized, having but little opportunity to escape.

I claim—

1. In combination with a horizontal boiler having a fuel-supplying magazine communicating directly with the fire-pot, a water-holding fire-box located under the boiler, and closed at all sides, and communicating by 90 pipes inclosed within the masonry or outer walls with the water in the boiler, all substantially as set forth.

2. In combination with a horizontal boiler having a fuel-magazine communicating by 95 curved feeding passages directly with the fire-pot, a spacious water-holding fire box or pot and hot-water pipes C C, each connecting the

upper part of such water-holding box with the water in the boiler, all substantially as and for the purposes set forth.

3. A water fire-pot constituting a spacious hollow water-chamber closed at all sides, provided with an extension or projection, and suspended or supported thereby in the masonry or casing of the boiler, combined with

two similar and inclosed tubes, C C, one on each side, severally connecting such water-chamber with the water-space in the boiler.

JOHN T. CORBETT.
